UNITED STATES PATENT OFFICE.

FRANK PHILIPPS, OF HAMMOND, INDIANA.

COLLAPSIBLE IRONING-BOARD STAND.

1,399,574.

Specification of Letters Patent.

Patented Dec. 6, 1921.

Application filed March 26, 1921. Serial No. 455,808.

To all whom it may concern:

Be it known that FRANK PHILIPPS, a citizen of the United States, residing at Hammond, in the county of Lake and State 5 of Indiana, has invented certain new and useful Improvements in Collapsible Ironing-Board Stands, of which the following is a specification.

The present invention relates to collapsible stands or supports for ironing boards, card table tops, and other devices with which it is desirable to have a knock-down and foldable support.

An object of the present invention is to 15 provide a relatively simply constructed and strong and durable stand or support, which may be easily and quickly set up into position of use, and knocked down into compact form for storing out of the way; and a 20 stand which, when set up, is interbraced and rigid, and which is capable of supporting relatively heavy weights, and which is adapted to remain stable under ordinary 25 conditions of use.

25 A further object of the invention is to provide a collapsible stand of this character which comprises a pair of similarly constructed members embodying the legs or supporting portions, and also the braces so 30 that these members may be set up and interlocked for forming the complete stand.

A still further object of the invention is to 35 provide a stand of this character which may be economically manufactured, and which, in use, requires no skill or practice in the setting up or knocking down of the parts.

The above, and various other objects and 40 advantages of this invention will be in part described in, and in part understood from, the following detailed description of the present preferred embodiment, the same being illustrated in the accompanying drawing, wherein:

45 Figure 1 is a side elevation of a stand or support constructed according to the present invention and in set up position for supporting an ironing board or the like;

Fig. 2 is a top plan view of the same;

50 Fig. 3 is a detail perspective view of one of the members or sections in position for assembly with its opposite like section;

Fig. 4 is a similar view of the opposite section with the brace thereof in collapsed 55 or folded position;

Fig. 5 is a fragmentary sectional view

taken through the lower end of one of the sections substantially on the line 5-5 of Fig. 1, showing the brace of the opposite section interlocked with the other section; 60

Fig. 6 is a horizontal section taken on the line 6-6 of Fig. 5, showing the parts interlocked.

Referring to the drawing by numerals, 65 and wherein like numerals indicate similar parts throughout the several views, the stand or support is shown as composed of a pair of similar or like uprights, and each upright is formed of a pair of crossed legs 10 70 and 11, which may be constructed of wood or other suitable material, and which are preferably mortised one within the other at their crossed or intersecting portions.

The upper ends of these legs 10 and 11 75 are joined by a cross piece 12 which is seated in one side of the legs which has its upper edge flush with the upper ends of the legs for forming therewith a flat supporting surface across which may rest an ironing board 13, or other suitable table top as may be desired. The lower ends of the crossed legs 10 and 11 are beveled off to provide lower ends adapted to bear flatly upon the floor or other support, and each upright or standard is provided with a brace 14 for rigidly holding the upright in set up 80 position.

Each brace 14 is provided intermediate 85 its ends, and in one lateral edge, with a 90 recess 15 extending to a depth substantially equal to one-half of the width of the brace 14, and the braces 14 are adapted to be interfitted at said recesses 15 for interlocking the braces one to the other for rigidly 95 holding the same in set up position. The braces 14 are connected by hinges 16 to the upper ends of the standards, one brace 14 being secured, as shown in Fig. 3, to the 100 upper left-hand corner of the adjacent standard, and the other brace 14 being hinged to the upper right hand corner of the opposed standard, as shown in Fig. 4.

By such an arrangement of the hinges, when the uprights are arranged opposite to each other, and with the braces extending toward each other, the braces 14 will be located at one side of the stand or support, as shown in Fig. 2, so that easy access may be had to the braces for interlocking and 110 releasing them.

The braces are adapted to extend diagno-

nally downward from the hinges 16 to the lower ends of the opposite uprights and are locked at their lower ends to the opposite uprights by means of laterally projecting 5 hooks 17, carried upon the free ends of the braces 14 and which are inclined downwardly at a suitable angle to lie flat against the inner faces of the opposite standards. The lower ends of the standards or up- 10 rights carry sockets or keepers 18 upon their inner sides and at their lower ends, in line with the braces 14 for the reception of the hooks 17 for interlocking engagement with the hooks to hold the braces firmly 15 from detachment.

The hooks 17 are preferably stamped from sheet metal with the body of the hook in the form of a yoke or seat, adapted to receive therein the lower end portion of 20 the brace. This yoke or seat is bent to conform to the configuration of the lower end of the brace, and thus rigidly holds the hook 17 thereto.

The sockets 18 each comprise, in the 25 present instance, a strip or length of sheet metal which is bent substantially U-shape with its free ends secured against the lateral edges of adjacent leg, such as the leg 10, and has its intermediate portion extending 30 across the inner side of the leg 10 and spaced therefrom to form the socket within the strip. The flat hook 17 is adapted to be inserted downwardly in the socket 18 and to then be shifted in an edgewise di- 35 rection for engaging the bill of the hook beneath one of the end portions of the strip 18.

When the stand or support is knocked 40 down and the braces 14 are separated one from the other, the braces 14 may be swung down against their respective uprights and are yieldingly held flat thereagainst by 45 spring clips 19 in the form of sheet metal devices, bent U-shape and secured against the inner sides at the lower ends of the legs 10, the free ends of the clips 19 projecting outwardly for receiving therebetween the lower end portions of the braces 14, as the latter are collapsed.

50 The stand or support itself comprises a pair of members or uprights, and each upright or member is provided with one movable part, a brace. These braces are so constructed that they may be interlocked 55 to each other and to the uprights for holding the entire device as a rigid trestle or stand. When the device is knocked down, it is folded into but two parts, the uprights. The braces carried by the uprights 60 are yieldingly held in collapsed position thereagainst so that there is no liability of loss of parts, or chance of breaking or mis- adjusting the various elements.

When it is desired to set up the stand 65 or table, it is only necessary to take the

pair of uprights, swing the braces 14 thereof out from the clips 19, and bring the uprights into position opposite each other by a slight lateral movement, sufficient to interlock the notched portions 15 of the braces, 70 for securing the same one to the other. After the notches have been interlocked, the hooks 17 are then moved into the sockets 18 and a slight further shifting of the uprights into position locks the hooks in the sockets. 75

The braces 14 are thus secured to each other and are also firmly anchored at their upper and lower ends to the opposite uprights. The result is that a relatively rigid and strong stand is provided.

It is of course understood that various changes and modifications may be made in the details of construction and design of the above specifically described embodiment of this invention without departing from 85 the spirit thereof, such changes and modifications being restricted only by the scope of the following claims.

What is claimed is:—

1. A stand for ironing tables and the like, 90 comprising a pair of standards, and a pair of braces carried one by each standard and adapted for detachable interlocking engagement with each other and each with one of the standards.

2. A stand for ironing boards comprising a pair of uprights, a brace carried by each upright and adapted to swing toward and from the same, said braces being adapted for detachable interlocking engagement 100 intermediate their ends, and detachable interlocking means carried upon the uprights and the free ends of the braces for securing the same to the opposite uprights.

3. A stand for ironing boards and the like comprising a pair of standards, a brace hinged to the upper end of each standard at the opposite registering corners thereof and said braces being adapted to be swung outwardly from the standards into crossed 110 relation and provided with notches intermediate their ends whereby the braces may be interlocked one to the other, hooks carried upon the free ends of the braces, and sockets carried upon the lower ends of the 115 standards for receiving said hooks when the device is set up for anchoring the free ends of the braces to the uprights.

4. A stand for ironing tables and the like comprising a pair of uprights, a brace 120 hinged upon the upper end of each upright and said braces being adapted to be swung outwardly from the uprights and into interlocking relation, means for anchoring the free ends of the braces to the opposite uprights, and means for yieldingly retaining the braces flat against the uprights when the braces are separated one from another and moved into collapsed position.

FRANK PHILIPPS,
